CLAIM

The ornamental design for an air cleaner cover, as shown and described.

DESCRIPTION

FIG. 1 is a front-right perspective view of an air cleaner cover according to the new design;

FIG. 2 is a front-left perspective view thereof;

FIG. 3 is a rear-left perspective view thereof;

FIG. 4 is a rear-right perspective view thereof;

FIG. 5 is a front elevation view thereof;

FIG. 6 is a rear elevation view thereof;

FIG. 7 is a right-side elevation view thereof;

FIG. 8 is a left-side elevation view thereof;

FIG. 9 is a top plan view thereof; and,

FIG. 10 is a bottom plan view thereof.

The broken lines show portions of an air cleaner cover which form no part of the claimed design.

1 Claim, 8 Drawing Sheets
